Joseph Michener
Petters Patent

The Schedule referred to in there Petters Patent and making part of
the same containing a description in the words of the said Joseph Michener
himself of his improvement in the mode of applying water on water wheels

A. Is the breast of the dam. B. Is the funnel to pass the water through
two inches at the bottom and eight inches at the top, thirteen inches
from B. to C.

C. D. Is the wall of the dam, inclines two inches back from
the centre of the water wheel to the top of the wall.

E. F. G. are the buckets eight in number to a 36 inch wheel in diameter

H. I. J. are the three
buckets that the water act on at a time, the arms are seven inches long
I claim the setting of the arms back which prevents the water falling to-
wards the shaft, which will give more power on the wheel, also the
inclination of the breast wall of dam and also the fall funnel and
applying the water on action of the water on three buckets at a time.
